UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF NEW YORK, N. Y., A CORPORATION OF DELAWARE.

INDEX OR FILE CARD.

Application filed October 19, 1923. Serial No. 669,524.

This invention relates to indexes or files of the class in which record members are arranged upon a frame or other carrying member in overlapped relation. More particularly the invention relates to a novel form of record member for use in such indexes, slidingly and detachably mounted upon a suitable guide and adapted to lie flatwise thereon under normal conditions, with a margin exposed to view below an overlapping similar member, the body portion of the same being covered.

In indexes of this type, it is desirable that the data upon the body of the record member be easily uncovered by manipulating the overlying card in order to observe the same or to make additions thereto or changes therein. It is also desirable to be able to remove a record member from the index and to insert another in place thereof. It is also desirable in such indexes to be able to insert additional cards adjacent ones already filed, upon which additional data in continuation of the data upon the adjacent card may be recorded when the adjacent card becomes filled. It is also desirable, in some instances, to change an index from the so-called box file into a visible index of the type under consideration, and therefore, indexes of this type should be provided with convenient means whereby this change may be easily and economically made.

The principal object of this invention is to provide in indexes or files or similar device, an improved record member having a base portion adapted to be detachably mounted upon a carrying member and which is capable of detachably supporting a card or other record-bearing member or a plurality of such members.

Another object of this invention is to provide in such indexes, suitable means for removably receiving and retaining record cards upon a guide in such a manner that additional cards may be added to, replacements made in, or cards taken from the index, without interfering with or disturbing the location of the cards already in place.

Other objects of this invention are to provide a record card holder adapted to receive

one or more cards and to hingedly retain the same, to decrease installation expense, to increase the range of usefulness of this type of index, and to generally improve record members whereby maximum efficiency is obtained by the use of the same.

To these and other ends, the invention consists in the novel features and combinations of parts to be hereinafter described and claimed.

In the accompanying drawings:

Fig. 1 illustrates a panel or leaf carrying record members embodying my invention;

Fig. 2 is a fragmentary front view of one of the record members shown in Fig. 1;

Fig. 3 is an end view of the same;

Fig. 4 is an enlarged view similar to Fig. 2, but with additional portions broken away or removed, for the sake of clearness;

Fig. 5 is a view of one corner of a record member;

Fig. 6 is a section on line 6—6 of Fig. 5;

Fig. 7 is a bottom edge view of a record member mounted upon a carrying member, which is sectioned horizontally beyond the card edges;

Fig. 8 is a view showing the operation of removing one portion of a record member from another portion;

Fig. 9 illustrates the operation of attaching and detaching one portion of a record member to and from another portion thereof;

Fig. 10 is a section on line 10—10 of Fig. 4;

Fig. 11 is a detail view of a hinged member used in connection with this invention;

Fig. 12 is a view of portions of a somewhat modified form of hinges for the record members.

In the drawings, a vertical supporting frame or leaf 20 has been shown provided with a record member guide 21, of the same general type as that shown in Patent No. 1,304,180, granted May 20, 1919, to R. D. Hayes. Record members 22 constructed in accordance with my invention are shown mounted upon the upper portion of the leaf 20, and are held flatwise thereon in overlapped relation, with a margin of each exposed to view, by the cooperation of connect-

- ing tongues or ears 23 with the flanged edges 24 of the guide 21, in the same general manner as that shown in Patent No. 1,048,056 granted December 24, 1912, to Irving Fisher.
- 5 An adjustable card support or stop 25 may be employed by which the cards are retained upon the upper portion of the leaf 20. The particular form of the card support or stop 25 forms the subject matter of a co-pending 10 application Serial No. 669,523, filed October 19, 1923, and is of interest here only as showing a suitable means to support the record members on the leaf in the position shown.
- 15 My improved record member or card 22 consists of a supporting or base portion 26, wherein are located the die cut ears or tongues 23, and a pair of record bearing portions 27 and 28 in the nature of sheets or 20 flaps. The base portion 26 is provided with a pair of hinge pintles 29 and 30, secured to an edge 31 of the same by clips 32. Each pindle projects beyond the clip 32 at each side thereof outwardly in respect thereto, as 25 at 33, and inwardly as at 34, and is secured to said clip against displacement relatively thereto by suitable securing means, such as insetting or staking the clip material as at 35.
- The clip 32 comprises a strip of material 30 folded back upon itself in such a manner as to form a pindle support or bearing portion 36, which is adapted to encircle the pindle. The ends of this strip are then extended outwardly as at 37, being spaced apart sufficiently to embrace the edge 31 of the base 35 portion 26. One of the ends is provided with pointed ears 38 which pass through the material of the record member base, and by being bent forwardly over the edge of the end 40 of the clip lying upon the reverse side of the card, the clip 32 is secured on the card. Similar clips 32^a are secured to an edge of each of the record bearing portions 27 and 28. One of the record bearing portions underlies 45 the other portion, 27 in this case, being shown as the underlying one. The clips secured upon the underlying record bearing portion 27 are preferably located to be engaged by the outwardly extending pindle portions 33, and when only one record bearing portion is 50 to be used, this is the preferred location for the clips 32^a. The overlying record bearing portion 28 has the clips 32^a secured thereto in proper position to be engaged by the inwardly extending pindle portions 34. The convenience of the above arrangement will be explained later.
- 55 By the use of a number of base portions 26 and a supply of clips 32^a, the cards of a box index, wherein the cards are filed one in back of the other, may be adapted for use in an overlapping visible-margined card index of the type illustrated. In such cases, the clips 32^a are secured to an edge of each of the 60 cards, preferably located so that they will be

engaged by the outwardly extending pindle portions 33. When necessary or desirable, additional cards may be added adjacent these original ones by securing other clips to the additional cards, locating the clips thereon in proper position to engage the inwardly extending pindle portions 34. The cards to be added may then be placed either above or beneath the original ones. When the device is to be used as above described to change one form of index to another, it is contemplated to furnish the user with the desired number of base portions having hinge pintles 29 and 30 properly secured thereto, and a plurality of card clips 32^a, in the form shown in Fig. 11. The clips in this case are open between the extending portions 37 to allow for the insertion of a card therebetween, after which the portions 37 are pressed together, by which action the card is pierced by the ears 38, which are then bent back over the other end portion 37, which lies on the reverse side of the card.

It is to be noted that when two record bearing portions or cards are mounted upon a base portion, as described above, the overlying card may be swung upwardly and away from the lower card and will lie substantially flat against the frame or the adjacent cards without the disadvantage usually present in hinged cards formed by creasing the card itself to form a hinged portion. This feature facilitates posting or reference and is one of the advantages contemplated by this invention.

In order to secure a card or record bearing portion 27 to the base portion 26, it is necessary to flex or buckle the base portion 26, as shown in Fig. 9, so that the pindle portions 33 may be engaged in bearing portions 36 of the clips 32^a. After being so assembled, the record member so formed may be secured upon the guide 21 by engaging the ears 23 under the flanges 24. When the record member is so engaged upon the guide 21, it is obvious that the record bearing portion 27 is locked upon the base portion 26, and is not detachable therefrom without first removing the base portion 26 from the guide 21. The card or record bearing portion 28 may be secured to or detached from the base portion 26 by flexing or buckling the record bearing member 28 to engage the bearing portions 36 of the clips 32^a with the inner pindle portions 34. It is obvious, therefore, that the record bearing portion 28 is attachable and detachable at will and may be secured to the base portion either in front of or in back of the record bearing portion 27.

In the modified form shown in Fig. 12, the base portion 39 of the record member is provided with clips 40 similar in construction to the clips 32^a, the clips 40 in this instance, presenting oppositely directed bearing portions instead of pindle portions. The cards 41 and

42 are provided with clips 43 having a pintle portion 44 extending outward from one side thereof. The clips 43 are similar for both cards but are secured to the cards so that the 5 pintle portions 44 extend in opposite directions at each end.

While I have shown and described my improved record member as being preferably used with a frame and card retaining guide 10 of particular design, I do not limit myself to the specific use therewith, as such a record member is obviously capable of advantageous use with other types of card carrying devices. Neither do I limit myself to a record 15 member in which a record bearing portion, when engaged by outwardly extending pintle portions mounted upon a base, is locked against removal therefrom, for under some conditions, it may be advisable or convenient 20 to cause the locking of the record bearing portion engaged by the inwardly extending pintle portion. It is desirable, however, that at least one of the same be locked in position upon the base portion, in order to insure that 25 the record members of the entire index be retained in proper sequence when in use.

While I have illustrated and described preferred forms of record members, embodying the features of my invention, it is to be understood that the same is not limited to the 30 exact details shown, as modifications and variations are possible which will lie within the spirit of the invention and the scope of the appended claims.

35 What I claim is:

1. In an index or file, a record bearing base member provided with means to detachably support a plurality of record bearing members, said means comprising in combination, 40 hinge pintles extending outwardly in opposite directions, and inwardly opposed hinge pintles.
2. In an index or file, a record bearing base member having means thereon for supporting a pair of record bearing members, comprising a pair of pintles, said pintles presenting outwardly extending portions in opposite directions and inwardly opposed portions.
3. In an index or file, a record bearing base member having means thereon for supporting a pair of record bearing members, comprising a pair of pintles, said pintles presenting outwardly extending portions in opposite directions and inwardly opposed portions, and a pair of record carrying members hinged to said pairs of pintles, respectively.
4. In an index or file, means to retain record members lying flatwise therein in overlapped relation, a card supporting member detachably secured to said retaining means, an index card, and a pair of hinge portions on said supporting member co-operating with a pair of hinge portions on said card to detachably connect said parts together, said

70 hinge portions being arranged relatively to said retaining means to lock said card against removal from said supporting member while said supporting member is retained upon said retaining means.

5. In an index or file, a card supporting member, a pair of index cards and means for hingedly connecting said cards to said supporting member, comprising a pair of oppositely directed hinge pintles mounted upon 75 said supporting member, and a pair of pintle-receiving portions mounted upon each of said cards.

6. In an index or file, a card supporting member, a pair of index cards and means for 80 connecting said cards to said supporting member, comprising a pair of hinge members having oppositely directed hinge portions mounted upon said card supporting member, and a pair of co-operating hinge portions secured to each of said cards.

7. In an index or file, a pair of index cards, a supporting member and means for hingedly interconnecting the same, said means including a double supporting hinge member having 90 oppositely directed pintles.

8. In an index or file, a pair of index cards, a supporting member and means for hingedly interconnecting the same, said means including an oppositely directed hinge bearing member and co-operating bearing member, one of said members being secured to said supporting member and the other being secured to said cards.

9. In an index or file, a record member 100 guide having nested overlapping record members slidably mounted thereon, each of said record members comprising a base and a plurality of separate cards and hinge members hingedly connecting said cards to said base, said hinge members adapted to allow any of said cards to be removed from said base independently of the remainder, and certain of said cards to be removed without disturbing the nested relation of said record 105 members.

10. In an index or file, a plurality of nested base portions slidably connected to a support, and a record portion comprising a plurality of cards, detachably hinged to each base portion.

11. In an index or file, a plurality of pairs of superimposed index cards, a plurality of overlapped members each adapted to hingedly support a pair of said cards, the hinges of said cards being adapted to permit removal of each card from said member independently of the other card.

12. A record device comprising a base member of flexible sheet material, a pair of 125 oppositely disposed integral tongues formed on said base member, a supporting member having a plurality of flanges adapted to receive said tongues so as to support a series of said base members in overlapping relation,

a plurality of superimposed cards, and hinge connections between said base member and cards.

13. A record device comprising a base member of flexible sheet material, a pair of oppositely disposed integral tongues formed on said base member, a supporting member having a plurality of flanges adapted to re-

ceive said tongues so as to support a series of said base members in overlapping relation, and a record-bearing member detachably hinged to each base member. 10

In witness whereof, I have hereunto set my hand this 12 day of October, 1923.

WILLIAM H. DAY.
